PASTE HOLDER AND DISPENSER

Rudolph H. Schwalm and Ernst Schwalm,
Millvale, Pa.

Application July 12, 1935, Serial No. 31,108

5 Claims. (Cl. 221—60)

The invention relates to a paste holder and dispenser and more especially to a holder and dispenser for tooth paste.

The primary object of the invention is the provision of a device of this character, wherein a collapsible paste container can be held and its contents automatically dispensed, the device being a wall bracket and in the construction thereof permits the introduction of a tooth brush 5 therein so that the contents of the container will be fed onto the bristles of the brush so that this brush will be supplied with a quantity of the contents for service in the cleaning of teeth during the use of the brush, the device in its entirety 10 being of novel construction.

Another object of the invention is the provision of a device of this character, wherein a tooth paste container such as a collapsible tube can be engaged in the device and held so that its contents 15 can be automatically dispensed therefrom and the tube at the cap end is confined in a socket so that this cap end will be automatically closed subsequent to the dispensing of the contents and such device avoids the necessity of manually 20 squeezing the tube for the collapsing thereof to dispense its contents as the squeezing of the tube is automatically effected and the contents delivered directly onto the tooth brush upon insertion of the latter within the device, the device 25 being thoroughly sanitary and is automatic in the working thereof.

A further object of the invention is the provision of a device of this character, wherein in the working thereof for the automatic dispensing of 30 paste from a collapsible tube it assures against waste of the contents of the tube and will enable the application of a quantity of the paste directly onto the bristles of a tooth brush, the latter being manually inserted in position to receive 35 the quantity of paste which is automatically dispensed by the device.

A still further object of the invention is the provision of a device of this character, which is simple in construction, thoroughly reliable and 40 efficient in its operation, enabling a collapsible paste tube to be fitted therein for the automatic dispensing of its contents, neat in appearance, constituting a wall fixture, strong, durable and inexpensive to manufacture.

With these and other objects in view, the invention consists in the features of construction, combination and arrangement of parts as will be hereinafter more fully described, illustrated in 45 the accompanying drawing, which discloses the preferred embodiment of the invention and pointed out in the claims hereunto appended.

In the accompanying drawing:

Figure 1 is a front elevation of the device constructed in accordance with the invention, show-

ing by dotted lines a collapsible tooth paste tube mounted therein and holding a tooth brush.

Figure 2 is a sectional view on the line 2—2 of Figure 1 looking in the direction of the arrows.

Figure 3 is a top plan view partly in section, the section being approximately on the line 3—3 of Figure 2 looking in the direction of the arrows.

Figure 4 is a sectional view on the line 4—4 of Figure 2 looking in the direction of the arrows.

Figure 5 is a top plan view of the squeegee 10 slide in open position.

Figure 6 is a top plan view of the guide frame for the squeegee and showing the retaining gate for the closed end of the tooth paste tube opened.

Similar reference characters indicate corresponding parts throughout the several views in 15 the drawing.

Referring to the drawing in detail, the device constituting the present invention comprises a base 10 preferably of outwardly bulged circular 20 form having a central circular nipple 11 for fitting therein of a tubular barrel 12 the latter having the closed inner end 13 while the opposite outer end is open and within this barrel accessible through the open end thereof is a socketed 25 valve-acting displaceable head or plunger 14 which is slidably fitted within the barrel 12 and operates against a coiled compression spring 15 fitting said barrel interiorly thereof and seated against the closed end 13 thereof. The socket 30 16 of the head or plunger 14 opens outwardly of the barrel 12 at its open end and accommodates therein the bristle end of a tooth brush 17, the bristles being indicated at 18 of this brush. This head or plunger 14 in its normal outward position closes a delivery port or opening 19 provided in the barrel 12 at the uppermost portion thereof and this port or opening 19 is centered with relation to a circular seat 20 walled by a modernistic shaped front facing plate 21 about the open 35 end of the barrel 12 and united therewith.

The barrel 12 at the lowermost portion thereof is provided with an elongated slot 22 receiving a guide screw 23 fastened in the head or plunger 14. The screw 23 has fitted therewith a stop dog 24 working in the slot 22 to limit the forward movement of the head or plunger 14. The dog 24 carries a hinged ratchet pawl or detent 25 co-active with a toothed ratchet wheel or gear 26 fixed to a windlass 27 journaled in the end walls 50 28 of the plate 21 beneath the barrel 12 so that when the head or plunger 14 works inwardly of the barrel 12 the pawl or detent 25 will engage the teeth of the ratchet wheel or gear 26 causing the windlass 27 to turn. On outward movement 55 of the head or plunger 14 the pawl or detent 25 will trip over the teeth of the ratchet wheel or gear 26 without disturbing the windlass 27 so that this windlass is rotated in one direction by said pawl or detent and only upon the inward 60

movement of the head or plunger 14 for a purpose presently described.

Rising above the seat 20 and fitted with the plate 21 is a collapsible tube holding frame including the channeled upstanding spaced parallel side members 29 and a channeled top cross member 30, respectively, these being united with each other. The cross member 30 is fitted with a hinged gate 31 so that the sealed closed end of a collapsible paste tube 32 can be engaged in the said member 30 and held clamped or secured thereto by the gate 31 when closed and latched in any suitable manner. This tube 32 at the cap engaging mouth end 33 thereof fits in the seat 20 and the contents of the tube on the collapsing of the same will be dispensed through the port or opening 19 when the head or plunger 14 has moved inwardly of the barrel and uncovered said port or opening 19. The head or plunger 14 is narrower at its uppermost portion than at its lowermost portion so that the bristled end of the tooth brush when engaged in the socket 16 with the bristles 18 thereof upstanding the paste dispensed through the port or opening 19 will be fed onto the bristles 18 of the brush 17 when the latter is at rest within the socket 16 within the head or plunger 14 and the latter has been moved inwardly of the barrel for uncovering the said port or opening 19.

Slidably fitted in the side members 29 is a squeegee which includes a runner 34 and a roller 35, respectively, the latter being journaled upon an arbor 36 hinged at 37 to the runner 34 at one end, the arbor at the end opposite the pivot 37 being formed with a latch 38 engageable with a keeper 39 on the runner 34 at the other end thereof remote from the pivot 37. The pivot 37 and the keeper 39 are in the form of eye pins 40 and to their eye terminals 41 are loosely connected the end portions of a flexible cable 42 it being trained through spaced holes 43 provided in the windlass 27 for the connection of this cable therewith so that the terminal stretches connected with the eyes 41 can be wound and unwound on and from this windlass on the turning thereof, the winding of the cable 42 being had automatically upon actuating the wheel or gear 26 by the detent or pawl 25 in a manner as before described. The winding of the cable 42 upon the windlass 27 causes the squeegee to be mounted when engaged in the side members 29 of the frame constituting the holder for the collapsible tube 32 and when the squeegee has the runner 34 engaged at one side of the tube 32 and the roller 35 at the other side with the arbor 36 for the latter latched with the keeper 39 the tube 32 will be automatically collapsed or squeezed for the dispensing of the contents from the said tube 32 through the port or opening 19. The squeegee is moved only when the head or plunger 14 is pushed inwardly against the resistance of the spring 15 within the barrel 12 by the tooth brush 17 when its bristled end is inserted in the socket 16 of said head or plunger. The terminal stretches of the cable or wire 42 are aligned and within the channeled side members 29 of the frame due to the locating of the holes 43 in the windlass and the eye pins 40 on the squeegee. The squeegee is insertable in the channeled side members 29 of the holding frame when this frame has its side members removed from the plate 21 by passing said squeegee through these ends into the channels in the side members. There is provided in the side members 29 next to the swinging gate 31 beneath the same notches or cut away

portions 44 so that the roller 35 of the squeegee can be opened when the latter is at these notches or cut away portions for the engagement of the tube in the squeegee and the fastening of the closed end of the tube by the gate 31 in the cross member 30 of said frame. Upon fastening the squeegee about said tube at the flattened closed end thereof by having the runner 34 at one side and the roller 35 at the other side of the tube when the squeegee is lowered on the winding of the wire or cable 42 upon the windlass 27 the said tube becomes pinched or collapsed for the squeezing of the contents within the tube to discharge or dispense such contents through the port or opening 19 uncovered by the head or plunger 14 when manually pushed upon through the instrumentality of the tooth brush 17, it being understood as previously stated that the squeegee does not operate except on the operation of the head or plunger so that tooth paste within the tube 32 will be delivered to the brush when the same actuates the head or plunger 14 of the device.

The seat 20 is provided with a resilient circular shaped or collar-like packing 45 for frictionally embracing the discharge end of the tube 32 and holding the same within the seat 20 without leakage of contents at this point in the working of the device or the accidental detachment of the discharge end 33 from the seat 20. The base 10 is provided with suitable openings or holes 46 for fasteners (not shown) so that the device can be made secure upon a wall to serve as a wall fixture within a bathroom or the like.

The latch end 38 of the squeegee carries a finger hold 47 which enables the unlatching of the squeegee when fitted within the holding frame on the positioning of the squeegee at the notches or cut away portions 44 in the side members 29 in this frame so that a tube 32 can be engaged in the holder and this is had by opening the gate 31 and engaging the closed end of the tube 32 in the member 30. Thereafter the gate 31 is closed which clamps the closed end of the tube to the frame and thereafter the roller 35 is brought into contact with the tube 32 by swinging the arbor 36 inwardly toward the runner 34 and fastening this arbor by the latch end 38 engaging the keeper 39. Thus the squeegee is now in position for collapsing the tube and the said tube 32 is clamped in the holder for the collapsing action of the squeegee upon the tube.

When the tube 32 has been completely collapsed or its contents dispensed therefrom the squeegee will be at the lowermost portion of the frame and then the tube 32 is unclamped from the holder so that the side members 29 of this holder can be disengaged or separated from the plate 21 from the device but before separation or disengagement the squeegee is opened to have the tube free therefrom. Thereupon the holder is separated or disengaged from the plate 21 and the tube is now free from the device to be discarded.

To place a filled tube within the holder the same is inserted in the plate 21 and the squeegee engaged in the side members 29 thereof is moved to the uppermost portion of the holder, it being understood, of course, that to move the squeegee to this position it must be closed. When the squeegee reaches the uppermost portion of the holder it confronts the notches or cut away portions 44 and the roller 35 can be swung outwardly by the opening of the arbor 36 and by opening the gate 31 the closed end of the tube can be clamped to the upper end of the holder.

and thereafter the roller 35 is swung inwardly against the tube and the arbor 36 latching the roller in this position by the latch 38 of the arbor engaging the keeper 39 so that the device is now 5 in a condition for the dispensing of the contents of the tube 32 on operation of the squeegee and the plunger or head 14 in a manner as herein-after set forth.

On opposite sides of the holder or the members 29 thereof are loops 41' each functioning as a hanger for the tooth brush 17, the latter being shown by dotted lines in Figure 1 of the drawing hung within one of the loops 41' of the device.

15 What is claimed is:

1. A device of the character described comprising a base, a tubular barrel carried by said base and open at its outer end, a socketed valve-acting plunger slidably fitted in said barrel and having its socket opening through the open end of said barrel, a facing plate at the open end of said barrel and having a seat for communication with said open end of the barrel and adapted to accommodate the discharge nipple end of 20 a collapsible tube, an upstanding frame releasably fitted with said plate and having guide side members, squeegee means operating in said side members and active upon the tube for the collapsing thereof, means at the upper end of the 25 frame for the fastening of the tube in suspended position within said frame when the nipple end is engaged in the seat, means acting upon the squeegee means for moving the same for effecting the collapsing of the tube and means co- 30 acting with the last-named means for automatic action of said last-named means on the shifting of the plunger.

2. A device of the character described comprising a base, a tubular barrel carried by said base and open at its outer end, a socketed valve-acting plunger slidably fitted in said barrel and having its socket opening through the open end of said barrel, a facing plate at the open end of said barrel and having a seat for communication 40 with said open end of the barrel and adapted to accommodate the discharge nipple end of a collapsible tube, an upstanding frame releasably fitted with said plate and having guide side members, squeegee means operating in said side members and active upon the tube for the collapsing 45 thereof, means at the upper end of the frame for the fastening of the tube in suspended position within said frame when the nipple end is engaged in the seat, means acting upon the squeegee means for moving the same for effecting the collapsing of the tube, means coacting with the last-named means for automatic action of said last-named means on the shifting of the plunger and means for fastening the squeegee means 50 about the tube.

3. A device of the character described comprising a base, a tubular barrel carried by said base and open at its outer end, a socketed valve-acting plunger slidably fitted in said barrel and having its socket opening through the open end of said barrel, a facing plate at the open end of said barrel and having a seat for communication 55 with said open end of the barrel and adapted to accommodate the discharge nipple end of a collapsible tube, an upstanding frame releasably fitted with said plate and having guide side members, squeegee means operating in said side members and active upon the tube for the collapsing 60 thereof, means at the upper end of the frame for the fastening of the tube in suspended position within said frame when the nipple end is engaged in the seat, means acting upon the squeegee means for moving the same for effecting the collapsing of the tube, means coacting with the last-named means for automatic action 65 of said last-named means on the shifting of the plunger, means for fastening the squeegee means about the tube, means within the barrel and active upon the plunger to normally hold the latter in a position to shut off communication 70 between the seat and said barrel, the said plunger having its socket of a form to accommodate the bristle end of a tooth brush and a sealing element within the seat to prevent leakage of the contents from the tube between its nipple end and said seat when engaged in the latter.

frame for the fastening of the tube in suspended position within said frame when the nipple end is engaged in the seat, means acting upon the squeegee means for moving the same for effecting the collapsing of the tube, means coacting 5 with the last-named means for automatic action of said last-named means on the shifting of the plunger, means for fastening the squeegee means about the tube and means within the barrel and active upon the plunger to normally hold the latter in a position to shut off communication 10 between the seat and said barrel.

4. A device of the character described comprising a base, a tubular barrel carried by said base and open at its outer end, a socketed valve-acting plunger slidably fitted in said barrel and having its socket opening through the open end of said barrel, a facing plate at the open end of said barrel and having a seat for communication with said open end of the barrel and adapted to accommodate the discharge nipple end of a collapsible tube, an upstanding frame releasably fitted with said plate and having guide side members, squeegee means operating in said side members and active upon the tube for the collapsing thereof, means at the upper end of the frame for the fastening of the tube in suspended position within said frame when the nipple end is engaged in the seat, means acting upon the squeegee means for moving the same for effecting the collapsing of the tube, means coacting 25 with the last-named means for automatic action of said last-named means on the shifting of the plunger, means for fastening the squeegee means about the tube and means within the barrel and active upon the plunger to normally hold the latter in a position to shut off communication 30 between the seat and said barrel, the said plunger having its socket of a form to accommodate the bristle end of a tooth brush.

5. A device of the character described comprising a base, a tubular barrel carried by said base and open at its outer end, a socketed valve-acting plunger slidably fitted in said barrel and having its socket opening through the open end 40 of said barrel, a facing plate at the open end of said barrel and having a seat for communication with said open end of the barrel and adapted to accommodate the discharge nipple end of a collapsible tube, an upstanding frame releasably 45 fitted with said plate and having guide side members, squeegee means operating in said side members and active upon the tube for the collapsing thereof, means at the upper end of the frame for the fastening of the tube in suspended 50 position within said frame when the nipple end is engaged in the seat, means acting upon the squeegee means for moving the same for effecting the collapsing of the tube, means coacting 55 with the last-named means for automatic action of said last-named means on the shifting of the plunger, means for fastening the squeegee means about the tube and means within the barrel and active upon the plunger to normally hold the latter in a position to shut off communication 60 between the seat and said barrel, the said plunger having its socket of a form to accommodate the bristle end of a tooth brush and a sealing element within the seat to prevent leakage of the contents from the tube between its nipple end 65 and said seat when engaged in the latter.
